UNITED STATES PATENT OFFICE.

ABRAHAM H. GOODWIN, OF NEW YORK, N. Y.

BOX SEAL.

Application filed May 20, 1925. Serial No. 31,602.

This invention relates to certain improvements in box seals and more particularly to that type in which the sealing device is a metal plate or strap with portions adapted to be driven into the wood of two adjoining walls of a wooden case for connecting them and preventing separation without mutilation of the seal or case.

As one important object of my invention, I so design the parts that each part is locked in place by nails which pass through the other parts and cannot be removed. In its preferred form, the seal includes two parts which engage with the outer surfaces of two adjoining walls of the box or other packing case and each of these parts has a perforated flange portion adapted to be driven into the wall of the box and held therein by a nail driven through the box wall, the other part and the perforation.

In the accompanying drawing, I have illustrated two embodiments of my invention. In these drawings,

Figure 1 is a perspective view of one type of shipping case with which my improved box seals may be employed,

Figure 2 is a transverse section through the corner of a box with the seal in position,

Figure 3 is a perspective view of one part of the seal shown in Figure 2,

Figure 4 is a perspective view of the other part and

Figure 5 is a perspective view of a nail which may be employed for connecting the parts and holding them in position.

I have illustrated my invention as applied to a shipping case having side walls A, end walls B, a bottom and top C. As illustrated each end wall has a marginal frame formed of four cleats D, secured to the outer surface thereof. Thus no one of the boards forming the end walls, can be removed without first removing one of the cleats forming this end frame. The box at each end has a second set of cleats E, which are secured to the sides, top and bottom, and which are connected together at their ends so as to form a second frame. The cleats E of this frame prevent the removal of any one of the side, top or bottom boards without first removing one of these cleats. The outer edges of one set of cleats overlap the adjacent edges of the other set. For instance the cleats D may have their outer edges terminating flush with the outer sides of the top, bottom and side walls, while the

cleats E project beyond said walls and cover the outer edges of the cleat D. I provide seals for connecting each cleat E to its adjacent cleat D so that none of the cleats 60 and none of the boards of any wall of the box can be removed without first removing or breaking the seal.

In the specific form of seal shown in Figures 2, 3 and 4, the body portion includes 65 two parts or sections adapted to be connected to the box in succession. One part is shown particularly in Figure 3, and includes a plate 10, a pair of end or terminal flanges 11 and 12, and side flanges 13 which are 70 preferably serrated so as to form a series of short sharp pointed teeth. The plate 10 is provided with a nail hole 14 which may be of a shape and size depending upon the character of the nail to be employed. For 75 instance, if it is desired to use a nail 15, cut from sheet metal with a flat, thin head, such as shown in Figure 5, the nail hole 14 may be in the form of a slot. If a round nail is to be employed, the nail hole 80 may be round. To accommodate either kind, the nail hole may be as shown in Figure 3, that is, in the form of a slot with an enlarged central portion adapted to receive either shape or type of nail.

The flange 12 has a similar nail hole 16^a in alignment with this is a nail hole 16 in the flange 11. The flange 12 also has a slot 17 between the nail hole 16^a and the plate 10 for receiving a flange on the other part 90 of the seal as hereinafter pointed out.

In Figure 4 there is shown the second part of the seal, which includes a plate portion 18 with end or terminal flanges 19 and 20 and serrated edge flanges 21. The flange 95 19 is of such size that it may enter the slot 17 of the part shown in Figure 3 and this flange has a nail hole 22 which will come into registry with the nail hole 14 when the flange 19 is extended through the slot 17. 100 The flange 20 has a nail hole 23 in registry with the nail hole 22.

In applying the seal shown in Figures 3 and 4, of a box case, the part shown in Figure 3 is first placed in position with the 105 plate 10 in engagement with one outer surface and the flange 12 in engagement with an adjoining surface. The part is driven into place by forcing the flange 11 into the wood forming one of the cleats E. With 110 this part in position, a nail 15 is driven into the cleat so as to pass through the nail holes

16^a and 16. The nail need not necessarily have any head as the outer end may come flush with the outer surface of the plate 10. If the nail have a head, the nail hole 16^a should be so countersunk as to permit the outer end of the head to lie flush with the surface of the flange 12. It will be noted that this nail 15 in passing through the nail hole 16, prevents the flange 11 from being drawn out of the wood.

After the plate 10 has been placed in position and secured by the nail 15, the other part is applied. The flange 19 is inserted through the slot 17 and the part is driven 15 into position by forcing the flanges 19 and 20 into the wood. The plate 18 extends across the joint between the cleats D and E, the flange 19 entering the cleat E and the flange 20 entering the cleat D. The serrated 20 flanges 21 are driven into the wood along the side edges of the flange 12 so as to prevent any one from forcing a tool beneath the plate 18 to pry the latter outwardly. After this part has been forced into position, a 25 second nail 15^a which may be similar to the nail 15 is driven through the aligned nail holes 14, 22 and 23. The head of the nail is forced in until it is flush with the outer surface of the plate 10, so that the nail cannot be engaged by pliers or other tool to withdraw it. The head of the nail 15 is protected by the plate 18 and the plate 18 is prevented from being withdrawn by the nail 15^a which passes through both terminal 30 flanges of the plate 18. Thus when the parts are in position the cleats D and E are connected and the connecting part is locked by a nail which is positioned by the hole 14.

I am aware that it has been proposed to 40 use box seals somewhat similar to that shown in Figure 4, but when such box seals are used alone, it is difficult to so position the nail that it will pass through the apertures of both flanges. In my improved construction, the position of the nail is determined by the hole 14 which is aligned with the nail holes 22 and 23. If one uses only the parts shown in Figure 4, the head of the retaining nail will be in the wood of the cleat E and can readily be removed with an ordinary nail puller, unless some special form of nail be provided. In my improved construction, I may employ any ordinary form of nail if the head is of such character that it may fit 45 into a countersunk nail hole.

Various forms of my invention may be designed within the scope of the appended claim. I do not wish to limit the use of the

box seal to the particular form of box or shipping case shown in Figure 1. The seal 60 may be used with various other forms of boxes or cases, although it is preferable to use it only in such positions where the flanges which are to be driven into the wood will lie in a plane lengthwise of the grain of the 65 wood, rather than across the grain.

It is preferable in forming the nail holes 16^a and 14, that the metal be forced up to form a short, outwardly projecting tube on the outer surface of the plate. This serves 70 as a guide for the nail so that the latter is more accurately directed to the holes in the flanges embedded in the wood therebeneath. Upon hammering the nail into position the metal forming this short upwardly or outwardly projecting tube, may be hammered down over the head of the nail as an additional protection against withdrawal of the 75 nail.

Having thus described my invention what 80 I claim as new and desire to secure by Letters Patent is:

A box seal including a pair of members, one including a plate portion adapted to engage with a side of the box adjacent to the 85 corner, and provided with a slot and a nail hole, the slot being disposed between the nail hole and the edge of the plate at the box corner, a second plate portion integral with the first mentioned plate portion and disposed at right angles thereto, and adapted to engage with an adjacent side of the box 90 and provided with a nail hole and a flange integral with the second mentioned plate portion and disposed at right angles thereto 95 and parallel to the first mentioned plate portion, said flange having a nail hole in alignment with the nail hole of the first mentioned plate portion whereby said member may be secured to the box by a nail driven 100 through the nail hole of the first mentioned plate portion, and thereby guided to the nail hole of said flange, and the other member including a plate portion adapted to be superposed on the first mentioned plate 105 portion of the other member, and including a pair of opposed parallel flanges having nail holes, and adapted to be driven into the box with one flange extending through said slot to bring the nail holes of said flanges 110 into alignment with the nail hole of the second mentioned plate portion.

Signed at New York in the county of New York and State of New York this 18th day of May, A. D. 1925.

ABRAHAM H. GOODWIN.
